US0D1100103S

(12) **United States Design Patent** (10) **Patent No.:** **US D1,100,103 S**
(45) **Date of Patent:** **** Oct. 28, 2025**

(54) **WATER RIDE FEATURE**

(71) Applicant: **ProSlide Technology Inc.**, Ottawa (CA)

(72) Inventors: **Richard D. Hunter**, Ottawa (CA);
Jonathan Brazeau, Richmond (CA)

(73) Assignee: **Proslide Technology Inc.**, Ottawa (CA)

(**) Term: **15 Years**

(21) Appl. No.: **29/966,909**

(22) Filed: **Oct. 7, 2024**

Related U.S. Application Data

(62) Division of application No. 29/889,794, filed on Apr. 17, 2023, now Pat. No. Des. 1,052,679.

(57) **CLAIM**

The ornamental design of a water ride feature, as shown and described.

DESCRIPTION

FIG. 1 is a top perspective view of a water ride feature showing our new design;

FIG. 2 is a bottom perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a right side view thereof; and,

FIG. 8 is a left side view thereof.

The broken lines show portions of the water ride feature that form no part of the claimed design.

1 Claim, 8 Drawing Sheets
